INVENTOR,

Otto K. Isensee;

BY *Otto K. Isensee*,

ATTORNEY.

UNITED STATES PATENT OFFICE.

OTTO K. ISENSEE, OF CHINO, CALIFORNIA.

ERASING AND POLISHING DEVICE.

1,379,922.

Specification of Letters Patent. Patented May 31, 1921.

Application filed May 20, 1919, Serial No. 298,385. Renewed April 19, 1921. Serial No. 462,797.

To all whom it may concern:

Be it known that I, OTTO K. ISENSEE, a citizen of the United States, residing at Chino, in the county of San Bernardino and 5 State of California, have invented new and useful Improvements in Erasing and Polishing Devices, of which the following is a specification.

This invention relates to improvements in 10 erasing, burnishing and polishing devices, and more particularly to the class in which spun glass is utilized as a medium whereby the erasing, burnishing or polishing is accomplished.

15 It has for its object to provide an improved holder means for holding a spun glass brush or cartridge so that same may be readily adjusted and put into operative position as it is used or worn away.

20 A further object is to provide a holder effectively utilizing a spun glass brush within it, and having at one end a rubber eraser so that said erasing, burnishing or polishing device may be utilized not only in the 25 burnishing of chinaware, or erasing of ink, but may be used to erase pencil marks as well.

In practising my invention I provide a holder having reduced end portions at either 30 end and corrugated portions adjacent to the reduced end portions or mouth-pieces, so that the holder may be gripped by the fingers without any fear of slippage in manipulating the device.

35 With the above and other objects in view, the invention consists in the novel features, construction, and unique combinations of parts and features, all as hereinafter fully described and claimed, the descriptive matter being supplemented by the accompanying drawing which forms a part of this specification.

In the drawing:

40 Figure 1 is an assembled view of the improved erasing, burnishing or polishing device;

Fig. 2 is a longitudinal sectional view, on an enlarged scale, of the device shown in Fig. 1;

50 Fig. 3 shows a spun glass erasing medium with a threaded ferrule at one end for holding same;

Fig. 4 is a fragmentary longitudinal view

of the device shown in Figs. 1 and 2, but showing the inner tube and its detail of construction;

Fig. 5 is an alternative method of arranging the polishing device without providing the rubber eraser means shown in Figs. 1 and 2;

Fig. 6 is a longitudinal view of the spun glass erasing brush with a threaded ferrule attached to one end and gripping same with a strip attached to said ferrule and running co-axially within the spun glass brush for a determined distance;

Fig. 7 is an end view of the device shown in Fig. 6 showing the head of the ferrule with a strip attached thereto;

Fig. 8 is a plan view of the knurled head shown in Fig. 5 and Fig. 9 showing the extended strip with its ends split and divergently directed and holding a washer means in position; and

Fig. 9 is a vertical sectional view of the knurled head with its washer shown in Fig. 8.

Corresponding parts in all the figures are designated by the same reference characters.

Referring particularly to the drawing, A designates improved holder means which utilizes both a spun glass brush and a rubber eraser. The holder means A comprises two tubular portions, an outer one *a* and an inner one *b*. The inner tubular portion *b* is illustrated in Fig. 4, as well as in Fig. 2. The inner tubular member *b* comprises a tubular head which is internally threaded as at 2 and is provided at one end with a reduced portion or mouth-piece 3 having a split portion 4 running co-axially with said tubular member *b*. The tubular member *b* is likewise provided with tapered helical threads 5. The mouth-piece 3 has a cut-out portion 6 which is used as a means for gripping the rubber eraser that fits within said mouth-piece. It will be observed that the reduced portion or mouth-piece has its sides 7 convergently arcuated toward a common axis for a certain distance and then said mouth-piece has its edges running parallel for a distance as at 8, in order to provide a portion of restricted size for the rubber eraser contained therein, and likewise to act as a guide for same. The outer tubular member *a* of the holder A is provided with

95
100
105

a mouth-piece 3^a similar in formation to the mouth-piece 3 just described, but instead of being provided with a tapered helical thread 5 is provided with a grip portion 9 which 5 is corrugated in formation. The opposite end of the tubular member *a*, that is, the end which does not have a mouth-piece, is provided with a circumferential bead 10, which bead fits within the annular recess 10 11 in the inner tubular holder *b*.

A sleeve 12 which is corrugated in formation and yet at the same time has its corrugations in a threaded form, screws upon the tapered helical thread 5 of the 15 tubular holder *b*. The brush *c* shown in Fig. 3 with its ferrule 13 screws within the inner tubular holder *b* along the threaded portion 2 of same. In assembling the device brush *c* is screwed within the inner 20 tubular holder *b* as shown in Fig. 2, and the outer tubular holder *a* with the sleeve 12 is slipped over the tubular holder *b*. The sleeve 12 is then screwed upon the tapered helical threads 5 of the holder *b*. The rubber eraser *d* is placed within the mouth-piece 3 before the sleeve is screwed on tightly. As will be observed, the tapered helical threads 5 have a constantly increasing diameter from the recessed portion 11 25 to the mouth-piece 3, and inasmuch as the inner tubular member *b* has a split portion 4 the action of screwing the sleeve 12 upon the threads 5, tends to close the split portion 4 and in doing so grips the rubber eraser *d* so that same will not slip when 30 the operation of erasing is performed. Obviously the spun glass eraser *c* can be moved inwardly or outwardly of the mouth-piece 3^a by turning the outer tubular holder *a* 35 while holding the inner tubular holder stationary by means of the sleeve 12. The spun glass brush *c* is rectangular in formation. If this were not the case or if the brush *c* were round the device would not 40 work, as will be readily understood. The sleeve 12 not only acts as a grip for the rubber eraser *d*, but likewise holds the beaded ends of the outer tubular member *a* 45 in position within the annular recess 11 of the inner tubular holder *b*.

An alternative method of providing a holder without a rubber eraser therein is shown in its various modifications in Figs. 5, 6, 7, 8 and 9.

55 In the device B shown in Fig. 5 it is not necessary to use a rectangular or angular brush, but a round one can be substituted. The device B comprises a tubular member *e* having a reduced end portion 14 and 60 internal threads 15 running the entire length of the tubular member *e*. A flanged knurled knob *f* has resting upon its flanged portions 16, an exterior helically threaded washer *g*. Likewise the knob *f* has connected to it a strip 17, which strip has 65

split end portions 18 and 19, said end portions being divergently directed and acting as a retaining means for holding the washer *g* in position upon the knob *f*. A small hole 20 passes through both the knob 70 *f* and the washer *g* and a pin may be inserted within this hole so that the washer *g* and the knob *f* may turn together. When the pin is removed the washer is free to rotate upon the knob *f*. 75

By referring to Fig. 7 it will be observed that the brush *c* is in this case round, and has passing through the threaded ferruled portion 13 the strip 17. This strip 17 passes co-axially downwardly within the brush *c* 80 and is the same strip that connects with the knob *f*. By inserting the pin through the hole 20 in the knob *f* and the washer *g*, the brush *c* may be placed within the tubular holder *e* and by turning the knob *f* 85 the threaded portion 21 of the washer *g* is screwed within the threaded portions 15 of the tubular holder *e*, after which the pin may be removed from the hole 20. It will now be observed that in order to move the 90 brush either inwardly or outwardly of the tubular holder *e*, all that is necessary is to turn the knob *f*, inasmuch as the washer *g* will not move. By turning the knob *f* the strip 17 which is rectangular in formation, 95 as above described, turns the brush *c* and the brush being held by the threaded ferrule 13, is caused to move along on the threaded portions 15 of the tubular member *e*. 100

In practising the invention I provide a spun glass eraser or cartridge treated with a resinous compound such as shellac, or the like, whereby the glass fibers may be confined to a definite area and the fibers maintained in a definite shape. This is a distinct advantage over the ordinary form or forms of glass erasers existing on the market at present, in that the ends of said glass erasers fray out, become uneven when using same, 110 break off, and if brushed by the hand, the glass fibers get into the pores of the skin, with resulting injury thereto. By treating the brush with shellac and allowing to dry, or pressing into form or baking as is necessary, the fibers wear off evenly when used, and yet at the same time wear off very finely so that brushing with the hand does not result in any injury thereto. 115

The spun glass when so treated stands up 120 firmly when projected from the holder, which is not true of the fibrous glass now used.

It is obvious that many changes may be made in the features of construction for carrying out the invention as described; however, these changes may be made within the scope of the invention as claimed, without sacrificing the principal advantages. 125

It will also be noted that by using a sub- 130

stance such as shellac the glass cartridge is not flexible. In fact, the resinous compound is hard and brittle and not tenacious enough to securely hold the glass fibers in 5 close relation to each other, excepting temporarily when in a holder. A rubbing of the glass brush C upon any substance when an end thereof is exposed through the mouthpiece 3^a will immediately cause the 10 shellac to let go of the glass fibers.

Having thus disclosed my invention, I claim and desire to secure by Letters Patent:

1. A device of the character disclosed, 15 comprising a tubular holder member, a surface-treating element housed within the holder member and adapted to project from one end thereof for application to a surface to be treated, and means coöperating with 20 the holder member to produce projection of such surface-treating element from one end of said holder member; said surface-treating material being provided with a threaded ferrule, and said tubular holder 25 member being internally threaded to co-act therewith; means being provided for turning said ferrule relative to said holder member to advance said surface-treating material; said surface treating material comprising an elongated mass of spun glass and 30 means associated with the mass of spun glass for maintaining the mass in a definite shape—said means being a resinous compound.

35 2. A device of the character disclosed, comprising a tubular holder member, a surface-treating element housed within the holder member and adapted to project from one end thereof for application to a surface 40 to be treated, and means coöperating with the holder member to produce projection of such surface-treating element from one end of said holder member; said surface-treating material being provided with a threaded 45 ferrule, and said tubular holder member being internally threaded to co-act therewith; means being provided for turning said ferrule relative to said holder member to advance said surface-treating material; a 50 mouth-piece being applied over said holder member and through which said material is adapted to be projected, said mouth-piece being rotatably connected with said holder member and being so formed as to 55 permit projection of said surface-treating material, but to prevent turning of the same within the mouth-piece.

3. A device of the character described, including an internally threaded tubular 60 holder, an elongated surface-treating element housed within the holder and adapted to be slidably projected beyond the same, a ferrule carrying the surface treating element and engaging the internal threads of 65 the holder, a member rotatable upon the

tubular holder, and means upon the rotatable member having an engagement with the surface-treating element and interlocking therewith to prevent relative rotation of the parts.

4. A device of the character described, including an internally threaded tubular holder, an elongated surface-treating element slidably mounted within the holder and comprising a mass of spun glass held together by a binder, a ferrule carrying the surface-treating element and engaging the internal threads of the holder, a member rotatable upon the tubular holder, and means upon the rotatable member slidably 75 engaging the surface treating element and interlocking therewith to prevent relative rotation of the said parts.

5. A device of the character described, including an internally threaded tubular holder, a surface treating element housed within the holder and adapted to be projected beyond the same, a ferrule carrying the surface treating element and engaging the internal threads of the holder, an outer 80 tubular shell housing the holder and swiveled thereon, and a head at the end of the shell which slidably engages the surface treating element and interlocks therewith to prevent relative rotation of the said 95 members.

6. A device of the character described, including a tubular holder having one end thereof split and provided at the base of the said split portion with a flared portion, 100 an eraser received within the split end of the holder, a sleeve threaded upon the flared portion and coöperating therewith to cause the arms of the split portion to grip the eraser, a surface-treating element slidable 105 within the tubular holder and projecting from the opposite end thereof, a ferrule carrying the surface-treating element and having a threaded engagement with the interior of the tubular holder, an outer tubular shell 110 housing the tubular holder and swiveled thereon, means maintaining the parts in such swiveled relation and a head at the end of the tubular shell slidably engaging the projecting end of the surface-treating element 115 and interlocking therewith to prevent relative rotation.

7. A device of the character described, including a tubular holder having one end thereof split and provided at the base of the 120 split portion with a flared portion and also with an annular depression, an eraser received within the split portion, a sleeve threaded upon the flared portion of the holder and coöperating therewith to grip the eraser, a surface-treating element slidably mounted within the tubular holder and projecting from the opposite end thereof, a ferrule carrying the surface-treating element 125 and having a threaded engagement with the 130

interior of the tubular holder, an outer tubular shell housing the tubular holder and rotatable thereon, said shell being formed with a rib received within the before-mentioned annular depression, means retaining the rib within such depression and a head at the end of the tubular shell provided with a portion which slidably engages the projecting end of the surface-treating element and

interlocks therewith to prevent relative rotation of the parts.

In testimony whereof, I have signed my name to this specification in the presence of two subscribing witnesses.

OTTO K. ISENSEE.
